Primary Examiner — Eliza Z Harvey*Assistant Examiner* — Landon Thomas Cassell**CLAIM**

The ornamental design for a foot spa tub as shown and described.

DESCRIPTION

FIG. 1 is a front perspective view of a foot spa tub showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, showing the foot spa tub in a folded state of use;

FIG. 9 is an enlarged detail view taken from portion 9 of FIG. 1; and,

FIG. 10 is an enlarged detail view taken from portion 10 of FIG. 2.

The broken lines in the drawings depict portions of the foot spa tub that forms no part of the claimed design. The broken lines in FIG. 1, FIG. 2, FIG. 9, and FIG. 10 depicting enlarged figures form no part of the claimed design.

1 Claim, 10 Drawing Sheets(56)
